DIAL ADDING MACHINE

William Calhoun Thompson, Seattle, Wash.

Application March 15, 1935, Serial No. 11,252

3 Claims. (Cl. 235—74)

My invention relates to dial operated adding machines in which one dial number rotor acts directly upon another to carry the tens. The objects of my invention are: To make this tens carrying direct action reversible so that it subtracts as well as adds with any number of dials; To expose a complementary total as well as a positive total, which when the total is below zero is the total below zero; To arrange the dialing numerals, the plus and minus totals, the dialing stops, the zero setting guides and the rotation direction indicators for easy understanding and easy correct operation; And to best adapt it to both the finger and the stylus operated sizes.

I attain these objects by the mechanism and markings illustrated in the accompanying drawings, in which:

Fig. 1 is a plan view of the framepiece upon which the working parts are to be mounted; Fig. 2, a plan view of the same plus the working parts mounted; Fig. 3, a front view of the assembly shown in Fig. 2; Fig. 4, a plan view, with cover added, of the complete finger operated size machine; Fig. 5 is a vertical transverse section of the same taken through line 5—5 of Fig. 4; Fig. 6, a plan view of a section of the framepiece of a small size stylus operated machine; and Fig. 7 is a plan view of a section of the complete small size machine; Fig. 8 is a front elevation partially in section of the modified type of assembly; and Fig. 9 is a vertical transverse section of the same taken through line 9—9 of Fig. 7.

Similar numerals refer to similar parts throughout the several views.

35 Dial rotors 1, which are in the general shape of a rounded straw hat, each of which are mounted on the framepiece 2, by means of an axially disposed dependent stub shaft 3 rotatably mounted at its lower end within its correlated hole 4 formed on the framepiece 2, with the steady effect of the rotor brims 5, resting on the stepped up planes 6, of the framepiece, in such a manner that each lower order number rotor brim overlaps without touching that of the next.

40 Each rotor is normally held in or moved to the nearest of ten definite positions by the pressure of a V shaped part of one of the springs 7, held by the framepiece, fitting into the wide part of one of ten inverted T shaped holes 8, 45 through the cylindrical side of its crown.

45 Snugly fitting over the outer edges of the framepiece 2 is a cover 9 adapted to normally enclose the assembly above described, said cover having a rectilinear row of openings 9a formed 50 therein in spaced relation, one for each of the

5 crowns 1a of the dial rotors 1, said openings being disposed in axially aligned relation with their correlated rotors, whereby an unobstructed view of the latter is obtained, see Fig. 4. Formed within the edge of each of said openings 9a above its 10 correlated crown 1a is a notch 10, whereby a portion of the brim 5 of the rotor 1 associated therewith is exposed to view for effecting reading of the numerals 19 upon the brim 5 in registration therewith. Similarly formed within the edge of each of said openings 9a below its correlated crown 1a and in substantially diametrically opposed relation to the notch 10 is a notch 11, whereby another portion of the brim 5 of the 15 rotor 1 associated therewith is exposed to view for effecting reading of the brim numerals 19 in progressive registration therewith.

Each rotor is dialed to add by placing a finger in the one of the dial holes 12, marked by the desired one of the digits 13, on the cover 9 of the 20 device, and then rotating it in the direction of the arrows through decreasing number positions to that of the zero of said digits 13 until said finger contacts a stop or projection 14 provided upon the cover 9 for each dial rotor 1, thereby limiting 25 dialing action of the rotor being actuated, as will be manifest and apparent.

Each dial is likewise operated to subtract by dialing the hole marked by the desired one of the smaller digits 15, which in both size machines 30 is on the framepiece showing through a dial hole 12, in the direction opposite to that for adding and therefore opposite to that of arrows, until a stop projection 14, stops the operating means with the dialed hole in the "0" position of the 35 second digits 15, across the stop from that of the digits 13.

Each rotor has one of the dial holes 16, distinguished from the others by one of the sector markings 17, on its crown. In the positions 40 where these sector markings fit into the extension markings 18, on the cover below the stops, the "0's" of the series of digits 19, are marked on the rotor brims 5, where they are exposed through the openings 10 in the cover above the 45 rotor crowns with the other consecutive digits marked on each in even spacing as the rotors are dialed to add.

As the rotors are rotated either way directly between the positions of each, thus exposing a "9" 50 and a "0", a rotor actuating tooth 20, extending out from each rotor brim, because of greater distance from its axis, first takes up a slight clearance space, then by engaging in the stem part of the T shaped holes 8, through the side of the 55

next higher order number rotor, effecting a tenth revolution thereof, and then moves through a similar space to prevent back action. This action correctly carries the tens for both adding and subtracting so that the series of the exposed digits 5 19 is the complete total of the machine when the total is not below zero, more easily read than the series of the digits 15 which show through the marked dial holes 16 of the rotors, which is 10 also the same number, the positive total.

Each rotor is set back to its zero total position without affecting any other rotor, by dialing the marked hole 16, backwards to the stop.

The openings 11 in the cover below the rotor 15 crowns, are so placed as to expose the numerals 21, of which all but one "10" are digits, marked 20 on the rotor brims between digits 19, thereon, in such a manner that on the lowest order number rotor the numeral 21, exposed is the ten 25 complement of the digit 19, exposed above, and on each of the other rotors it is the nine complement thereof. When the last total digit 19, is "0", its complement below is "10", making 30 desirable the printed direction on the cover: "If 25 '10', carry to next figure," which also applies to all figures made ten thereby, as on all rotors when they are all in the zero positions, which makes the "9, 9, 9, 10". of the four rotors shown 35 read "0, 0, 0, 0". The complete number thus read 40 is the round number one greater than the highest possible total for the machine, complement of the total above, and is the total below zero when the total is below zero.

To help the operator avoid mistakes in the 35 direction of dialing the rotors which alternates in the rotors to add and opposite to that to subtract: The stops 14, are on the side of each rotor that is dialed downward to add, giving a "feel" 40 check to both the operating the right way and the operating the right rotor instead of the next one; Pointers are marked on each rotor and on the cover, indicating the direction to operate each to add.

In the slightly modified type of stylus operated 45 calculating machine illustrated in Figs. 6 to 9, inclusive, the numeral 1' designates dial rotors of the same shape as the rotors 1 which are mounted upon their framepiece 2' substantially 50 in the identical manner hereinbefore described for said rotors 1, said rotors 1' having brims 5' and being mounted upon stepped up planes or 55 portions 6' of the framepiece 2'. Each of the rotors 1' is normally held in or moved to the nearest of ten definite positions by the pressure of a V-shaped portion of a spring 7' mounted upon the framepiece 2', which V-shaped portion is 60 adapted to progressively engage a series of inverted T-shaped openings or slots 8' provided in the cylindrical walls of the crown portion 1'' of said rotor 1'.

Snugly fitting over or upon the outer edges of the framepiece 2' is a cover 9' having a rectilinear row of openings 90 formed therein in spaced relation, one for each of the crowns 1'', 65 of the dial rotors 1', said openings being disposed in axially aligned relation with their correlated rotors, whereby an unobstructed view of the latter is obtained, see Fig. 9. Formed within the edge of each of said openings 90 above its 70 correlated crown 1'' is a notch 10', whereby a portion of the brim 5' of the rotor 1' associated therewith is exposed to view for effecting reading of the numerals 19' upon the brim 5' in registration therewith. Similarly formed within the 75 edge of each of said openings 90 below its cor-

related crown 1'', and in diametrically opposed relation to the notch 10', is a notch 11', whereby another portion of the brim 5' is exposed to view for effecting reading of the brim numerals 19' in progressive registration therewith.

Each rotor 1' has one of its dial holes 16' distinguished by a sector marking 17', and in the position where the latter registers with an extension marking 18' on the cover 9', the zero of the series of digits 19' are marked on the rotor 10 brim 5', where it is exposed to view through its correlated opening 11'. Stylus stops 14' are provided upon the framepiece 2' in radial alignment 15 with the markings 18', such stops being disposed in annular alignment with the annular row 15 of second digits 15'.

Each rotor 1' is provided with a perimetral tooth 20' adapted to engage, when rotated, the T-shaped slots 8' of the rotors 1' immediately adjacent thereto. In the larger or stylus 20 operated machine which is adapted to permit both an adding and a subtracting dialing digit to show through each dial hole, the adding digit 13', is on the side in the hole that the rotor it shows through is turned downward to add, and the subtracting digit 15', on the side the rotor is turned downward to subtract. Such features as the total 25 openings 10', the negative total openings 11', the stop projections 14', the zero setting sector extension markings 18', the word "Stop" indicating the 30 positions of two stops, the word "Cents" between the last two rotors and the word "Dollars" between the two before those, are all on adjacent sides of each pair of rotors, starting with the last two paired, all of which emphasizes the fact that 35 downward between each pair is the direction to dial each to add.

I am aware that adding mechanisms have been invented without intermediate gearing between the number rotors, so do not make this broad 40 claim, but

I claim:

1. In a calculating machine the combination of a base having a series of numbered dials upon the upper face thereof, a reversible rotor for each 45 of said dials rotatively mounted upon said base in axial alignment with its correlated dial and provided with a concentrically disposed crowned portion, each of said portions having a series of peripheral apertures formed therein and an annular row of apertures formed within the upper 50 wall thereof for registration with the numbers on its correlated dial, a perimetric tooth on each of said rotors, the tooth of a lower order rotor being adapted to engage the peripheral apertures 55 of the next higher order rotor, detent means for each of said rotors adapted to releasably engage the peripheral apertures thereof, and a cover provided with a series of openings through which said crowned portions normally project.

2. In a calculating machine the combination of a base having a linear row of numbered dials upon the upper face thereof, a reversible rotor for each of said dials rotatively mounted upon said base in axial alignment with its correlated dial and provided with a concentrically disposed 65 crowned portion, each of said portions having a series of T-shaped slots formed in the periphery thereof and an annular row of apertures formed within the upper wall of same for registration with the numbers of its correlated dial, a perimetric tooth on each of said rotors, the tooth of a lower order rotor being adapted to engage the peripheral slots of the next higher order rotor, 70 yieldable detent means for each of said rotors 75,

5 having V-shaped terminals adapted to releasably engage the peripheral T-shaped slots thereof, and a cover provided with a row of linear openings through which said crowned portions normally project, each of said openings having a stop projecting inwardly from the edge thereof.

10 3. In a calculating machine the combination of a base having a linear row of numbered dials upon the upper face thereof, a reversible rotor for each of said dials rotatively mounted upon said base in axial alignment with its correlated dial and provided with a concentrically disposed crowned portion, each of said portions having a series of inverted T-shaped slots formed in the periphery thereof and an annular row of apertures formed within the upper wall of same for registration with the numbers of its correlated dial, an annular row of numbers upon the mar-

5 ginal portion of each of said rotors, a V-shaped marginal tooth on each of said rotors, the tooth of a lower order rotor being adapted to engage the reduced upper portions of the inverted T-shaped peripheral slots of the next higher order rotor, 10 resilient detent means for each of said rotors having V-shaped terminals adapted to releasably engage the enlarged lower portions of the inverted T-shaped slots thereof, and a cover provided with a series of openings through which 15 said crowned portions normally project, each of said openings having a stop projecting inwardly from the edge thereof and having oppositely disposed notches formed in said edge wherewith the numbers upon the marginal portions of said 15 rotors progressively register.

WILLIAM CALHOUN THOMPSON.
